UNITED STATES PATENT OFFICE.

CLARENCE B. HARLOW, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

CIRCUIT-CLOSER.

1,308,711.

Specification of Letters Patent.

Patented July 1, 1919.

Application filed March 3, 1915. Serial No. 11,756.

To all whom it may concern:

Be it known that I, CLARENCE B. HARLOW, a citizen of the United States, residing at Chicago, in the county of Cook and State 5 of Illinois, have invented new and useful Improvements in Circuit-Closers, of which the following is a full, clear, concise, and exact description, reference being had to the accompanying drawing, forming a part of 10 this specification.

My invention relates to improvements in circuit closers, and has for its object to provide a circuit closing device particularly adapted for closing the circuit of an electric 15 horn or signal device. The circuit closing device is intended primarily for use on automobiles and like vehicles, and one of the objects of my invention is to provide a neat, compact switch which may be operated by 20 pressure from almost any direction, and which is rigidly and economically constructed.

For the purpose of disclosing my invention I have illustrated an embodiment there- 25 of in the accompanying drawings.

In the drawings,

Figure 1 is a side elevation of a circuit closer showing the manner in which it is secured to a support;

Fig. 2 is a vertical axial section of the circuit closer showing the manner in which the contacts are secured to the insulating base, and showing the relation of the movable contact to the operating device;

Fig. 3 is a horizontal section on the line 3—3 of Fig. 2 showing a plan view of the movable contact;

Fig. 4 is a horizontal section on the line 4—4 of Fig. 2; and

Fig. 5 is a bottom view of the circuit closer showing the manner in which the binding plates are seated in the recesses in the lower part of the insulating base.

Referring now to the drawings in detail 45 the circuit closer comprises an insulating base 10 for supporting the contacts and the binding posts, a casing or housing 11 for the insulating base and contacts, and an operating member 12 for engagement with the

hand of the operator which is so constructed 50 that pressure on it in almost any direction will cause the circuit to be closed. The base 10 has in its lower face a pair of recesses 13 in which are located the binding plates 14 to which the binding screws 15 are se-

cured. The binding plates are held in place in the recesses by means of rivets 16 extending through openings 17 in the base 10. One of these rivets 16 also extends through an opening 18 in the movable contact 19 to 60 secure the latter to the base 10. The movable contact 19 comprises a U-shaped portion 20, an upwardly inclined portion 21, a horizontal portion 22 for engagement with the operating member, and a downwardly 65 inclined portion 23 which is so constructed that when the portion 22 is depressed the portion 23 will be moved into contact with the rivet 16 which is located beneath it. The casing 11 comprises an elliptical flange 70 24 for engagement with a suitable support 27, the flange being provided with a pair of openings 25 through which screws 26 are inserted to secure the device in place, and comprises also a cylindrical portion 28 into 75 which the base 10 is inserted, the casing above the cylindrical portion 28 being reduced as shown at 29 to limit the distance to which the base 10 may be inserted within the casing, and comprises also an inwardly 80 extending annular flange 30 which forms a fulcrum member for the operating member 12. The operating member 12 comprises a mushroom-shaped cap or button 31, a flange member 32 for engaging the fulcrum flange 85 30, a hollow rivet member 33 having a flange 34 embedded in the bottom 31, and an insulating washer 35 which is seated within a cup portion 36 of the flange member 32, and through which the hollow rivet 33 extends 90 to hold the washer 35 and flange member 32 onto the bottom 31. The conductors 37 may lead through an opening 38 in the support 27, to a position in which they may be engaged by the binding screws 15. The movable contact 19 has an opening 39 therein directly above the rivet 16, this opening being provided to enable the upper end of the rivet 16 to be flanged over after it is inserted through the opening 18 in the contact 19. 100

The spring tension in the movable contact 20 is such as to normally hold the operating member 12 in its raised position shown in Fig. 2.

By the arrangement above described the 105 cap or button 31 is maintained in what might be termed a floating position while being at the same time connected to the casing, so that whenever pressure is applied to the top of the button the contact 23 will be 110

5 moved into engagement with the hollow rivet 16 and the circuit thereby closed. Also if pressure is applied at any point along the side or at any point on the periphery of the 10 cap 31 it will be tilted, the flange 30 forming a fulcrum to prevent the side opposite from that to which the pressure is applied from rising so that the cap will be tilted on the side on which the pressure is applied to 15 move the movable contact into engagement with the stationary contact.

15 The cap 31 may be provided with a downwardly extending flange or skirt 40 which will help to make the circuit closer water proof. The base 10 may be provided with laterally extending channels 41 (Fig. 5) leading from the recess 13 to the side of the base, and the casing may be provided with an opening 42 in its side, the purpose of the 20 channels 41 and opening 42 being to enable the circuit closer to be wired from the side by leading the conductors in through the opening 42 and channels 41 in case it is inconvenient or not desirable to lead the conductors in through the bottom of the casing.

Having thus described my invention what I claim as new and desire to secure by Letters Patent is:

1. A circuit controller comprising a contact, a movable contact coacting therewith, a metallic housing therefor having an annular flange forming a fulcrum, an insulating hand-engaging member, a metallic fulcrum-engaging member having a flange engaging 35 said first flange, means for securing said fulcrum engaging member to said hand-engaging member comprising an insulating washer, and a rivet extending through said washer to hold the washer on the hand-engaging member and to engage the movable contact.

2. A circuit controller comprising an insulating base, a stationary and a movable contact carried by said base, a housing for 45 said contacts having a flange forming an annular fulcrum, a tiltable cover overhanging said housing, a ring having a portion thereof engaging beneath said flange to lock the housing and cover together, a washer secured to the under side of said cover and 50 clamping said ring to the cover, and a rivet

having one end embedded in said cover and having its opposite end turned over said washer for holding the washer to said cover.

3. The combination with a cylindrical casing having one end enlarged, an insulating base fitting within said enlarged part of the casing, a stationary contact mounted on said base, a movable spring contact mounted on said base coöperating with said stationary contact, said casing having a flange at its upper end forming an annular fulcrum, a tiltable overhanging cover for said casing, a fulcrum engaging ring mounted on the under side of said cover for locking the cover and casing together, a central rivet embedded at one end in said cover, and an insulating washer clamping said ring to the cover and secured thereto by said rivet.

4. The combination with a cylindrical casing having one end enlarged and having a pair of flat oppositely-disposed securing lugs formed on the bottom of the casing, an insulating base fitting within said enlarged part of the casing and having on its bottom 70 a bifurcated channel, binding plates carrying binding screws mounted on said base in each leg of the channel, a stationary and a movable contact mounted on the opposite face of said base, rivets extending through the base securing the plates in position, one of said rivets forming the stationary contact and the other rivet securing the movable contact in position, said casing having an opening therein coinciding with the bifurcated channel in the base, and having at its 75 upper end a flange forming an annular fulcrum, a tiltable overhanging cover for said casing, a fulcrum-engaging ring mounted on the under side of said cover for locking the cover and casing together, a central rivet embedded in said cover and an insulating washer fitting over said rivet and secured in place thereby and clamping said ring to the cover.

In witness whereof I have hereunto subscribed my name in the presence of two witnesses.

CLARENCE B. HARLOW.
